(57) **CLAIM**

The ornamental design for a vent trim for oven as shown and described.

DESCRIPTION

FIG. 1 is a front perspective view of a vent trim for oven shown in an environment of use;

FIG. 2 is an enlarged detailed view of portion 2 shown in FIG. 1;

FIG. 3 is a top perspective view of the vent trim for oven;

FIG. 4 is a bottom perspective view thereof;

FIG. 5 is a front elevational view thereof;

FIG. 6 is a back elevational view thereof;

FIG. 7 is a left side elevational view thereof;

FIG. 8 is another enlarged detailed perspective view of the right end of the vent trim for oven;

FIG. 9 is a top elevational view of the vent trim for oven; and,

FIG. 10 is a bottom elevational view thereof.

The oven shown in broken lines in FIGS. 1 and 2 is environment and forms no part of the claimed design. All other evenly dashed broken lines in FIGS. 1-10 represent portions of the vent trim for oven and form no part of the claimed design. The dot-dash lines illustrate the border of the enlarged detailed views and form no part of the claimed design.
